S. GOODCHILD

MEANS FOR DELIVERING MEASURED QUANTITIES

Filed Nov. 21, 1925

Inventor:
Stanley Goodchild

By Harold D. Penny
Notary

UNITED STATES PATENT OFFICE.

STANLEY GOODCHILD, OF TEDDINGTON, ENGLAND, ASSIGNOR TO RIDGWAYS LIMITED,
OF LONDON, ENGLAND, A COMPANY OF GREAT BRITAIN.

MEANS FOR DELIVERING MEASURED QUANTITIES.

Application filed November 21, 1925, Serial No. 70,573, and in Great Britain November 27, 1924.

This invention relates to means for delivering measured quantities and it has for its object to provide simple and efficient means whereby measured quantities may be discharged from containers for tea or other goods.

According to this invention there is provided at a convenient point upon the top of the container an opening through which 10 the goods are discharged.

Running downwardly from the said opening within the container is a partition which may be of flat or other suitable cross-sectional outline said partition extending to 15 a point somewhat above the bottom of the container in a manner such as to form a passage having an opening at the lower end.

Arranged outside the first partition and extending downwardly from a suitable distance beneath the top of the container is a second partition arranged in spaced relationship to the first partition, the lower end of said second partition being inclined inwardly and downwardly below the opening 25 of the first partition.

In order that the invention may be the better understood drawings are appended in which:—

Fig. 1 is a part sectional elevation showing the invention applied to a metal canister for containing tea,

Fig. 2 is a similar view showing a modification.

Referring to the accompanying drawings 35 *a* indicates the body of the canister the upper end of which is provided with a closure *b*. *c* indicates a removable closure whereby the canister is filled.

Referring to Fig. 1, the closure *b* is provided at *b* with an opening of triangular outline disposed at one corner of the canister. Running downwardly from the inner edge or base of the triangular opening is a plate *e* the longitudinal edges of which are secured by soldering or otherwise to the two adjacent sides of the canister. The plate *e* is of such length as to extend to within a certain distance of the bottom of the canister forming a passage the discharge end of 45 which terminates at the aforesaid opening in the closure *b*.

Disposed outside and in close relationship to the plate *e* is a second plate *e*, also soldered or otherwise secured at its edges to

the walls of the canister, the upper end of 55 which plate is disposed at a suitable distance below the closure *b* whilst the lower end is bent inwardly beneath the plate *e* being suitably tapered as to enable it to snugly engage the side walls of the canister. 60

It is to be noted that the length of the outer plate *e* is such that it extends well above the opening at the lower end of the first plate so that a comparatively large amount of tea is collected therein. 65

When the canister is filled the tea passes down the space between the inner plate *e* and the outer plate *e* the quantity to be delivered being collected at the bottom of the said inner plate *e*. When the canister is 70 inverted only the material at the bottom of the two plates is discharged, or is it possible to shake any further quantity out, as the tea outside the inner plate falls downwards, that between the plates *e*, *e* then 75 being at a lower level than the opening at the bottom of plate *e*. The return of the canister to its normal position causes a fresh quantity to enter between the plates *e*, *e*, ready for the next discharge. 80

It will be seen that as there are no projections upon which the tea may collect when the canister is inverted the whole of the contents of the canister may be discharged. 85

In the alternative arrangement shown in Fig. 2, the measuring device is arranged on the side of the canister the outer plate, indicated by *f*, in this case being of semi-conical form, whilst the inner plate, indicated by *f*, is of semi-circular form. 90

In order to prevent the discharge of the contents, when so desired, a removable strip of cardboard or other material may be inserted as shown at *x*, Fig. 1. 95

The forms of the invention illustrated and described are given by way of example only and are not in any way intended to limit the form or application of the invention, which may be applied to receptacles of 100 round or other cross-sectional outline.

I claim:—

Means for delivering measured quantities from polygonal containers comprising a triangular opening at the corner of the top closure thereof, a partition extending between two adjacent side walls of the container, the upper end of said partition being coinci- 105

dent with the base of said triangular opening, said partition extending to a point above the bottom of the container, and a second partition outside and in spaced relationship to said first partition and also extending between the said side walls of the container, the upper end of said second par-

tition being disposed at a point below the closure, said second partition having a bottom inclined portion laying beneath the lower end of the said first partition.

In testimony whereof I have hereunto set my hand.

STANLEY GOODCHILD.
